UNITED STATES PATENT OFFICE.

HARRISON B. WALTER, OF DANVILLE, ILLINOIS, ASSIGNOR TO NATIONAL FIBRE BOX COMPANY, OF DANVILLE, ILLINOIS, A CORPORATION OF ILLINOIS.

KNOCKDOWN BOX.

1,045,648.

Specification of Letters Patent. Patented Nov. 26, 1912.

Application filed April 3, 1912. Serial No. 688,210.

To all whom it may concern:

Be it known that I, HARRISON B. WALTER, a citizen of the United States, residing at Danville, in county of Vermilion and State 5 of Illinois, have invented certain new and useful Improvements in Knockdown Boxes, of which the following is a specification.

My invention relates to an improvement in knock down boxes which may be flattened out when in the knocked down condition so that it will occupy a minimum of 10 space and will afford support not only at the edges but also at the center for its fellows stacked thereabove.

15 Further objects are to provide simple means for fastening the box when set up and ready for use as well as for knocking it down when not in use.

In the accompanying drawings, Figure 1 20 is a view of the box in its knocked down condition. Fig. 2 is a horizontal section through the box in its set up condition. Fig. 3 is a detail view. Fig. 4 is a modification.

The present invention comprises a sheet 25 of material bent to form top 1, bottom 2, sides 3 and 4, as well as flap 5 by creasing along the line 6—6. At the edges cleats 7, 7 are secured. These are preferably of wood and beveled at their ends whereby adjacent edges fit each other and form a miter joint when the box is set up and around the outside thin metal strips 8, 8 are secured, the tacks extending through the material 30 of which the box is made, and also through the cleats as well as through the metal strips, 35 and at the ends of the flap the metal strips extend beyond the top of the box as at 9, 9 and are adapted to overlap the edge of the adjacent member, preferably the top of the 40 box when the box is set up and secured together.

Two different methods of constructing the ends are illustrated, one in Figs. 1 and 2, in which each end is composed of two partially overlapping flaps 10 and 11, the outer 45 edges of which are secured between the sides of the body portion of the box and the cleats adjacent to which a bend 12 is formed. These flaps are of sufficient length to partially overlap each other and they are provided with registering orifices 13, 13, in one

end of which a hollow corrugated metal button 15 is held by friction in position to enter the orifice in the corresponding flap from the other side when the box is set up 55 and the two orifices register or come opposite each other. No fastening is required although one may be used if desired by making these corrugations in the buttons in the form of screw threads and securing a 60 cap thereover after the assemblage of the parts, but no cap is really required, as the pressure of the contents within the box when filled will give the required lateral support to hold the flaps outward and together. The 65 length of these buttons preferably corresponds to the depth of the cleats so that in the knocked down condition of the box a support is formed approximately midway between the cleats upon which the body portion of 70 the box next above rests. In the modified construction these ends would be the size of the end of the box thus overlapping each other throughout their full area so that each end would be in two thicknesses of the 75 material, reinforcing each other and giving added strength and support. In this way a very simple but useful knock down box is provided of few parts, five pieces of material in all save the cleats and metal strips, 80 which of course are additional, all of which are easily and quickly assembled and when in commercial condition, require no skill to set them up or knock them down, thus making a desirable shipping case for the market 85 which may be manufactured at a small initial cost, and which, when in use, will be most effectual in the shipping and storing of the goods it may contain.

Having thus described my invention, 90 what I claim and desire to secure by Letters Patent is—

1. A knock down box comprising a sheet of material bent to form top, bottom and sides, end cleats, end flaps, the outer edges 95 of which are secured between the cleats and the body portion of the box, and the inner ends of which are adapted to overlap from opposite sides of the box and provided with registering orifices adapted to receive fastening means whereby the overlapping ends are secured together. 100

2. A knock down box comprising a sheet of material bent to form a top, bottom, and sides, mitered cleats secured to the edges thereof and end flaps having registering orifices therein and means adapted to extend through said orifices to secure the overlapping ends of the end flaps together.

In testimony whereof I affix my si
in the presence of two witnesses.

HARRISON B. W.
